Geo. Adcock

BY *Penry J. L. Adcock*

ATTORNEY

UNITED STATES PATENT OFFICE

GEORGE ADCOCK, OF WALNUT GROVE, CALIFORNIA

APPARATUS FOR PACKING ASPARAGUS

Application filed May 20, 1929. Serial No. 364,505.

This invention relates to the packing of fresh asparagus in crates, my principal object being to provide an apparatus, arranged to be temporarily associated with a crate, by means of which the asparagus as cut in the field may be placed in the crate, the ends of the stalks all trimmed simultaneously so as to be the same height, and the remaining slats of the crate then nailed in place, all in a continuous series of operations. By this means not only are packing operations considerably expedited over ordinary methods which require different handling of the asparagus between the cutting and the final crating of the same, but the neat appearance of the crated product is increased over ordinary packs to such an extent as to bring asparagus packed with my improved apparatus a higher price in the open market.

20 A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a cross section of the apparatus arranged in connection with a crate in position and with the asparagus being initially placed therein.

Fig. 2 is a similar view showing the crate as filled and the asparagus being clamped while the ends of the stalks are trimmed.

Fig. 3 is a perspective view of the apparatus and crate, the latter being fully packed and their side slats nailed in position.

Fig. 4 is a perspective view of the apparatus with the crate removed.

Referring now more particularly to the characters of reference on the drawings, the apparatus which is in effect a crate supporting cradle comprises horizontal supporting bars 1 adapted to span a washing tray 2 and rest on the sides thereof. Secured to and projecting upwardly from the inner faces of these bars are plates 3 of substantially tri-

angular form with their apices above and more or less central between the ends of the bars. Secured to the inner faces of the plates and extending downwardly and transversely from the front edges of the same are flanges 4 connected at their rear lower ends by a cross flange 5. Diagonal braces 6 connect the flanges 4 and 5 so that the structure is made rigid.

The flanges 4 are parallel to the upper rear edges of the plates 3 and the distance between said flanges and edges is approximately that of but not less than the height of a crate from the upper surface of its top slats 7 to the bottom edges of the end boards 8. The distance between the side plates 3 is slightly greater than the exterior length of the crate so that the latter may be freely placed in position between said plates.

Other transverse flanges 9 are secured to the inner faces of the plates and project upwardly from the plane of the cross flange 5 in spaced relation thereto, said flanges 9 being connected at their upper ends by a cross flange 10 preferably disposed at the level of the top of the rear sloping edges of said plates. The flanges 9 and 10 are disposed so as to be not quite parallel to the front edges of the plates 4, or so as to be at the same converging slope relative to said edges as the side edges of the crate boards of the "pyramid" type commonly used in asparagus packing. Also the distance between said flanges and the front edges of the plates is substantially the same but not greater than the width of the crate from the outside of the side slats 11 to the opposite side edges of the end boards 8. The structure above described thus forms a means for supporting a crate at an angle to a horizontal plane, so that it is in position to enable the asparagus stalks 12 to be conveniently placed therein with their tips down.

The crate being set bottom side up the bottom slats and the front side slats are left off temporarily, while the top slats and those of the other or back side are left in place. Before placing any asparagus in the crate however a temporary asparagus supporting board 13 is placed in the crate a sufficient distance above the top slats 7 thereof so that the

roughly cut ends of all the stalks will project above the level of the rear upper edges of the plates 3. This plate is adjustably supported in place, so that the distance from its upper 5 surface to said upper edges of the plates may be varied according to the length of the asparagus being handled, by means of adjustable screws 14 engaging the under surface of said board both at the back and front. The 10 board is limited in its movement inwardly of the crate, so that it cannot slip through by a bar 15 secured along its front and extending beyond the side edges of the plates to engage the front edges thereof.

15 The board above mentioned being in place the asparagus is placed in the crate, the bundles as picked up being first dipped in the trough to wash them, the water draining back into the trough when the asparagus is placed 20 in the crate, due to the slant which the crate naturally has while in the cradle. When the crate is completely filled so that the front stalks project in front of the plates 3 somewhat, they are compressed in place by a bar 25 16 which extends between said plates across the front thereof and intermediate the top and bottom of the crate. The bar at one end is flexibly and removably pivoted in connection with one plate and at its other end removably engages a catch hook 17 fixed on the 30 other plate. A knife 18 of suitable character is then drawn across the upwardly projecting ends of the stalks, said knife resting on and being guided by the front upper edges of the 35 plates.

40 The upper ends of all the stalks are therefore trimmed off to the same level so that all the stalks will be the same length. The front side slats 11a of the crate are then nailed in position while the clamping bar is still in place, so that the stalks cannot bulge out and interfere with nailing operations. The position of this bar of course is such as to offer no interference with the placing of these slats in their customary locations.

45 The bar is then withdrawn so that the crate may be removed from its supporting cradle to enable the bottom slats to be then nailed on, or said slats may be nailed on while the 50 cradle is still in position on the cradle. The board 13 is withdrawn after the bottom slats are nailed on and the crate is in its upright position so that the tips of the stalks will remain on the same level and will present a 55 neat appearance when the top slats are later removed with the retailing of the asparagus.

60 From the foregoing description it will be readily seen that I have produced such a device as substantially fulfills the objects of the invention as set forth herein.

65 While this specification sets forth in detail the present and preferred construction of the device, still in practice such deviations from such detail may be resorted to as do not form a departure from the spirit of the

invention, as defined by the appended claims.

Having thus described my invention what I claim as new and useful and desire to secure by Letters Patent is:

1. Apparatus for use in connection with the packing of asparagus in a crate comprising a cradle having flanges to support an initially open sided and bottomless crate in an inverted position to enable the asparagus to be packed therein, and a clamping bar 75 removably associated with the front of the cradle to engage the adjacent row of asparagus when the crate is packed to press the asparagus into the crate and facilitate the nailing of the front side-slats of the 80 crate in place thereon.

2. Apparatus for use in connection with the packing of asparagus in a crate comprising a cradle having flanges to support an initially open sided and bottomless crate in 85 an inverted position to enable the asparagus to be packed therein, with the tips pointing downwardly, a board removably associated with the cradle to project across the crate area above and parallel to the inverted 90 top thereof to form a temporary support for the asparagus tips and to enable the butts of the asparagus then projecting above the crate, and knife guiding means, parallel with the board, provided with the cradle at the 95 ends of the crate.

3. A structure as in claim 2, with means for adjusting said board to and from said guiding edges without disturbing the crate.

4. A structure as in claim 2, with means for temporarily clamping the asparagus against movement after the crate is packed to enable the upwardly protruding ends of the asparagus to be trimmed off without 100 displacing any of the asparagus stalks from their packed position.

5. Apparatus for use in connection with the packing of asparagus in a crate comprising a cradle having flanges to support an initially open sided and bottomless crate 110 in an inverted position to enable the asparagus to be packed therein, and means provided with the cradle for supporting the same from a fixed horizontal surface while causing the inverted top of the crate to have 115 a downward transverse slope from front to rear.

6. Apparatus for use in connection with packing asparagus in a crate comprising a cradle having means to support an initially open sided crate with the open side in an upwardly facing position to enable the asparagus to be placed therein, and clamping means associated with the cradle 120 to engage the row of asparagus adjacent the open side of the crate when the latter is fully packed and press the asparagus into the crate to facilitate the nailing of the side slats onto the crate.

7. Apparatus for use in connection with 125

packing asparagus in a crate comprising a cradle having means to support an initially open sided and bottomless crate in an inverted position to enable the asparagus to be packed therein with the tips pointing downwardly, and means removably associated with the cradle to form a temporary support for the tips above the inverted top of the crate to cause the butts of the asparagus to project above the crate whereby to enable said butts to be then cut off flush with the crate.

8. A method of packing asparagus in a crate having its bottom slats and those of one side initially removed, including supporting the crate with said bottom and open side facing upwardly, placing the asparagus in the crate with the tips toward the actual top of the same, pressing the row of asparagus adjacent the open side inwardly of the plane of the same when the crate is fully packed, and placing the slats of said side in position on the crate while the asparagus is thus held pressed.

25 In testimony whereof I affix my signature.
GEORGE ADCOCK.
